United States Patent Office

Des. 176,066
Patented Nov. 15, 1955

176,066

SHOE

David Evins, New York, N. Y., assignor to Johnston & Murphy, Newark, N. J., a corporation of New Jersey

Application May 18, 1955, Serial No. 36,079

Term of patent 7 years

(Cl. D7—7)

FIG. 1.

FIG. 2.

Fig. 1 is a view in top plan of a shoe showing my new design.

Fig. 2 is a view in side elevation of the outer side of the shoe.

The dominant features of the design reside in the portions thereof shown in full lines in the accompanying drawings.

I claim:

The ornamental design for a shoe, as shown and described.
